UNITED STATES PATENT OFFICE.

ERNEST TIMMERHOFF, OF ELKHART, INDIANA, ASSIGNOR OF ONE-HALF TO CHARLES E. TEED, OF ELKHART, INDIANA.

RADIATOR-CAP.

1,239,542.

Specification of Letters Patent. Patented Sept. 11, 1917.

Application filed March 14, 1917. Serial No. 154,887.

To all whom it may concern:

Be it known that I, ERNEST TIMMERHOFF, a citizen of the United States, residing at Elkhart, in the county of Elkhart and State of Indiana, have invented certain new and useful Improvements in Radiator-Caps, of which the following is a specification.

My invention relates to improvements in radiators for cooling internal combustion engines, and has for its object the provision of a radiator cap which may be readily and quickly attached and detached, and which is provided with an opening for the radiator which will permit of the rapid filling thereof.

Other objects of the invention are to provide a radiator cap which may be so quickly handled in the application or removal thereof, that practically no difficulty is had in handling the same when highly heated, the facility with which same may be handled thus tending to promote a more frequent inspection of the water supply, which is more or less neglected under circumstances making the inspection more difficult. Furthermore, as the radiators are usually filled with water carried in a container, such as a bucket or can, I so form the radiator opening that the contents of the container may be more quickly emptied than is possible with the conventional round opening.

With the above and other objects in view, the invention in its preferred form of details will be described in the following specification, reference being had particularly to the accompanying drawings, in which:—

Figure 1 is a fragmentary perspective view of a radiator showing the application 40 of my invention.

Fig. 2 is a longitudinal sectional view partly in elevation of the removable cap.

Fig. 3 is a longitudinal sectional view of the structure forming the opening into the 45 radiator.

Fig. 4 is a top or plan view of the assembly.

By referring to the drawings, it will be seen that the opening for the radiator 1, 50 consists of an upstanding flange or collar 2, which is elliptical in form, so that the same will have a considerable greater dimension in length than in width, one of the objects of which is to permit a greater flow 55 of water to enter through the opening from

a container than is possible through a round opening having the same area, due to the fact that in pouring from a container the stream spreads flat, as is well understood, the volume of flow, without spilling, being 60 limited by the distance between the opposing walls of the opening. In this respect it is assumed, of course, that the container is held close to or rests upon the flange forming the opening, as is the usual practice. 65

As illustrated, the flange 2, which is formed of any suitable metal, is bent inwardly upon itself, as at 3, its edge 4 terminating short of the lower edge of the flange, said edge 4 being provided with oppositely 70 disposed notches 5, for a purpose presently explained.

Adapted to rest upon the upper edge of the flange 2, is a detachable cap 6 having a body portion 7, which conforms in plan 75 with the shape of the flange 2, and provided with a downwardly projecting marginal flange 8 adapted to overlap the outer marginal edge of the flange 2 when the cap is resting on the latter, as shown in Fig. 1. 80 The cap is provided with a centrally disposed and inwardly projecting cylindrical housing 9, entirely open at its upper end and closed at its lower end. A knob 10, provided with a boss 11 on its under side and 85 adapted to partially project into the housing 9, is provided with a stem 12 of a length to project from the boss through an aperture 13 in the end of the housing, to end 90 of which stem there is fixed a catch or locking bar 14. Interposed between the boss 11 and the end of the housing 9, and encircling the stem 12, is a helical spring 15 tensioned to normally hold the locking bar 95 against the end wall of the housing. In applying the cap to the flange 2, the knob 10 is depressed with the locking bar disposed lengthwise of the cap, as shown in Fig. 2, and given a half turn to bring the ends 16 of the locking bar in engagement 100 with the oppositely disposed notches 5 of the flange 2, when the knob is released and the action of the spring serves to yieldingly hold the bar in locking engagement with said notches. To unlock and remove the 105 cap, a slight downward pressure on the knob and at the same time giving same a turn unlocks the cap, when the same may be lifted from its seat. The rapidity with which the cap may be locked and unlocked 110

- forms the salient feature of the invention, as the same may be handled when highly heated without danger of receiving burns in the handling, as distinguished from the 5 greater amount of manipulation necessary in the removal of a cap having a screw-threaded connection with the radiator, with the attendant difficulty of handling a highly heated cap.
- 10 While the foregoing is the preferred form of my invention, I desire it to be understood that I do not limit myself to the precise structure shown and described, as it is obvious that the same may be variously modified without departing from the spirit of the invention.
- It will be noted from the foregoing description, taken in connection with the drawings, that the improved radiator cap is positively locked in place by the engagement of the locking bar in the notches 5, and hence, when once secured, the separation of the parts is not possible under any vibrations or jars to which the vehicle may be subject- 20 ed. Furthermore, the formation of the flange 2 is such as to provide an effective strengthening, while at the same time permitting a simple formation of the notches 5, in that said notches are provided by cutting the edge of the material before the same is formed in the return bend to strengthen the flange. Furthermore by terminating the return bend portion of the flange above the lower edge of the flange 30 35 proper provision is made for the co-operation of the locking bar therewith, dispensing with the securing of additional means in place for this purpose.
- It will be further noted that the diametri- 40 cally opposed notches are arranged in line with the minor axis of the flange, and hence there is but one position in which the locking bar will engage the notches to lock the cap in place.
- 45 In any other position than the locking po-

sition the cap is free, and it will be at once apparent that this materially facilitates the application and removal of the cap.

What is claimed is:

1. The combination with a receptacle having a filling opening, of an upstanding flange secured to the receptacle above and beyond the opening, said flange being of elliptical form in plan and of double thickness of material from the upper edge thereof to a point above the lower edge, the free edge of the innermost section of material being formed in line with the minor axis of the flange with locking notches, a cap to engage the free upper edge of the flange and means carried by the cap to engage said locking notches to secure the cap in place, said means being wholly freed of all locking connection with the cap when out of line with minor axis of the flange, whereby the cap is locked to the flange in one position of the locking means and free of the flange in all other positions of such means. 55
2. The combination with a receptacle having a filling opening, of an upstanding flange secured to the receptacle above the opening, said flange being of elliptical form and having an annular edge portion on the inner side thereof between the upper and lower edges, said annular edge portion being formed with downwardly opening notches in line with the minor axis of the flange, a cap to engage the upper edge of the flange, and a locking bar carried by and movable relative to the cap to engage the 60 notches, said bar having a length coextensive with the internal minor axis of the flange below the notched edge thereof, whereby the bar when in line with the minor axis of the flange will lock the cap in place and in any 65 other position will permit free movement of the cap relative to the flange. 70 75

In testimony whereof I affix my signature.

ERNEST TIMMERHOFF.
